ADJUSTABLE OARLOCK SLEEVE

Frank William Fraser, Vancouver, British Columbia, Canada

Application March 18, 1936, Serial No. 69,548
In Canada February 3, 1936

1 Claim. (Cl. 9—24)

This invention relates to an improved adjustable oarlock sleeve.

An object of the present invention is the provision of an oarlock sleeve that may be fitted to oars 5 of any of the standard sizes.

Another object is the provision of an oarlock sleeve that may be firmly mounted on the oar without the necessity of using long nails or the like which weaken the oar.

10 A further object is the provision of a device of this character of strong and simple construction and which may be very easily manufactured.

Heretofore it has been necessary to provide a different sized oarlock sleeve for each type of oar 15 manufactured. Another disadvantage of the known oarlock sleeves is that they are formed with an enlarged flange made up of a series of layers of leather secured to each other and to the oar by means of a plurality of long nails or 20 the like which extend into the oar in substantially the same plane, thus weakening the oar at the point where there is the greatest strain.

The present invention overcomes these objectionable features by providing a split sleeve 25 formed of rubber, leather, fabric or any other suitable material having an enlarged split flange or shoulder with a metal ring embedded therein and means for adjustably securing the sleeve to an oar as more fully described in the following 30 specifications and illustrated in the accompanying drawing, in which,

Fig. 1 is a transverse section through the flange,

Fig. 2 is a longitudinal section taken on the line 2—2 of Fig. 1, and

35 Fig. 3 is a perspective view of the sleeve mounted on an oar shaft.

Referring more particularly to the drawing, A is a section of an oar shaft and B is the adjustable oarlock sleeve which comprises a tubular 40 member or sleeve 10 split at 11. Said sleeve 10 is preferably formed of rubber but it may be formed of leather, fabric or other suitable material. At one end, the sleeve 10 is formed with a relatively thick flange or shoulder 12 split radially at 13, said radial split being aligned with the split 11.

45 Embedded in the flange 12 is an open reinforcing ring 14 the free ends of which are formed with lugs 15 and 16 and terminate at points 50 spaced from the split 13. The lugs 15 and 16 extend outwardly to the periphery of the flange and are provided with aligned orifices, the orifice in the lug 15 being internally screw-threaded. A bolt 17 is adapted to extend freely through the 55 orifice in the lug 16 and to be threaded through

orifice in the lug 15. The ring 14 extends substantially the full width of the flange 12.

Said flange 12 is recessed at 18 on one side of the split 13 and at 19 on the other side of said split, the latter recess opening out on the periphery of the flange at 20 in order to allow the bolt 17 to be inserted in the lugs 15 and 16.

If desired, the ring 14 may be provided with a vertical flange 21 which terminates adjacent to the lugs 15 and 16. This flange is desirable 10 when the oarlock sleeve B is formed of leather but may be used with other materials as well. The flange 21 re-inforces the portion of the flange 12 lying outside the ring 14. Since the lugs 15 and 16 re-inforce the flange 12 around 15 the recesses 18 and 19, it is not necessary to have the flange 21 extend all the way around the ring 14.

A plurality of short screws or nails 22 are used 20 to fasten the sleeve 10 to the oar shaft A. These screws or nails are spaced from the split 11.

These oarlock sleeves are all manufactured, as shown in the drawing, to fit the largest standard sized oar manufactured. If it is desired to fit the sleeve onto a smaller oar shaft, it is only 25 necessary to cut away from each side of the splits 11 and 13 a suitable amount of the material from which the sleeve is made as, for example, along the dotted lines 23. The screws 22 and the lugs 15 and 16 are so spaced from the splits 11 and 13 30 as to allow for the reduction of the sleeve to any of the standard sizes. The lugs 15 and 16, by extending to the periphery of flange 12, act as 35 guides for the cutting operation.

The sleeve is adjustably fitted onto the oar 35 shaft in the following manner: when the bolt 17 is removed from the lugs 15 and 16, the sleeve is slipped onto the oar shaft and moved to the desired position and then the bolt is replaced in the lugs and tightened by means of a screw 40 driver inserted through the opening 20 into the recess 19. The recess 18 is large enough to accommodate the end of the bolt 17 when the sleeve is reduced to its smallest possible diameter. This operation is completed by inserting the 45 screws 22 which are quite short so that they do not in any way weaken the shaft of the oar. In this way the adjustable sleeve is firmly mounted on the oar shaft without the use of relatively long 50 fastening means.

The metal ring 14 and flange 21 brace the sleeve at the point where there is the greatest strain and yet does not add materially to the production cost.

These adjustable oarlock sleeves may be manu- 55

factured in large quantities in one size since they are capable of being fitted on any standard oar. Another advantage lies in the fact that they may be applied to the oars by unskilled persons whereas in the past considerable skill was necessary. Also, with the known types of sleeves it is almost impossible to take them off one set of oars and apply them to another set. This may be done many times with the present device without damaging it.

What I claim as my invention is:

An adjustable oarlock sleeve comprising a tubular member, an enlarged flange formed with the

member, said member having a split aligned with a radial split in the flange, an open ring embedded in said flange the free ends of which are spaced from the split in the flange, orificed lugs formed on the ends of said ring extending outwardly to the periphery of the flange to act as guides, a vertical flange extending around the ring and terminating adjacent to said lugs, said enlarged flange and tubular member being adapted to be cut away between the lugs to fit 10 oars of various sizes.

FRANK WILLIAM FRASER.
